United States Patent Office

Des. 177,690
Patented May 15, 1956

177,690

FONT OF PRINTING TYPE

Ray F. Morgan, Northfield, Ill.

Application November 17, 1955, Serial No. 38,935

Term of patent 14 years

(Cl. D64—12)

The drawing is a face view of a font of printing type showing my new design.

I claim:

The ornamental design for a font of printing type, as shown.
